Primary Examiner — Paula Greene(74) *Attorney, Agent, or Firm* — Andrew W. Chu; Craft Chu PLLC**CLAIM**

The ornamental design for a communication device, as shown and described.

DESCRIPTION

FIG. 1 is a perspective view of the communication device showing my design.

FIG. 2 is a rear elevation view thereof;

FIG. 3 is a front elevation view thereof;

FIG. 4 is a top plan view thereof, including protrusion attachments in broken lines; and,

FIG. 5 is a bottom plan view thereof.

The broken lines form no part of the claimed design.
